UNITED STATES PATENT OFFICE.

EDWARD J. DEITSCH, OF NEW YORK, N. Y.

DESIGN FOR A BELT.

SPECIFICATION forming part of Design No. 30,922, dated May 30, 1899.

Application filed April 3, 1899. Serial No. 711,605. Term of patent 34 years.

To all whom it may concern:

Be it known that I, EDWARD J. DEITSCH, residing in the city of New York, borough of Manhattan, county and State of New York, have invented and produced a new and original shape or configuration, a Design for a Belt, of which the following is a specification, reference being had to the accompanying drawings, forming part thereof, of which—

- o Figure 1 of the drawings illustrates a perspective view of the belt having its free ends tied, and Fig. 2 illustrates a perspective view of the belt with the front ends untied.

A A' represent two parts of the belt. Each of the two parts of the belt consists of an upper and a lower band a a'.

b is a knot by which the two parts of the belt are connected detachably together upon the rear portion thereof when the belt is not in use.

c c' represent two loops or stays by which the upper and lower bands of the two parts of the belt are secured one upon the other near the free ends thereof, and these stays are located in such a manner as to hold the upper and lower bands in substantially the same vertical plane.

To the free ends of the two parts of the belt are secured pieces or strips of leather or other suitable material d d'.

e is a band connected to the free end of part A' between the two bands a a' thereof and under the stays c', by means of which the opposite free ends of part A may be drawn to and firmly secured to the opposite free end of part A'.

The features of my design consist of a two-part belt, each of which parts is doubled, having rounded and plaited bands lying one upon the other, with loops at their free ends and tied or knotted together at the rear portions of the said parts. The front looped free ends of one of said parts has connected to it a tie-band.

The belt is made of leather, but may be made of any other suitable material.

Having described my invention, what I claim as new, and desire to secure by Letters Patent, is—

The design for a belt herein shown and described.

In testimony whereof I have hereunto affixed my signature in presence of two witnesses.

EDWARD J. DEITSCH.
